THOMAS GARRICK, OF PROVIDENCE, RHODE ISLAND.

Letters Patent No. 104,443, dated June 21, 1870.

IMPROVED MACHINE FOR FEEDING STOCK TO EYELET-MACHINES.

The Schedule referred to in these Letters Patent and making part of the same.

To all whom it may concern:

Be it known that I, THOMAS GARRICK, of Providence, in the county of Providence and State of Rhode Island, have invented certain Improvements in Machines for Feeding Stock to Eyelet-Machines, of which the following is a specification, reference being had to the accompanying drawing.

My invention relates to the manufacture of eyelets; and

It consists in a novel construction of a machine for feeding the stock to the machine or dies that form the eyelet, as hereinafter more fully explained.

Figure 1 is a transverse vertical section on the line $z z$ of fig. 2;

Figure 2 is a front elevation;

Figure 3, an end view from one end; and

Figure 4, a similar view from the opposite end.

Figure 5 represents a piece of the stock or strip of metal, detached.

To construct my improved device, I provide a suitable frame, A, and mount therein a pair of feed-rolls, B C, which are connected by spur-gears $h f$, on one end, as represented in fig. 2, the gear being shown more clearly in fig. 4.

In one of these rolls, B, I form, circumferentially, a series of circular or oval recesses, n , as represented in fig. 2, this series of recesses extending entirely around the roll, and are connected, one to another, by a small passage-way or channel, which is narrower than the recess itself.

In practice the recesses are made somewhat oval in form, and are cut into each other at the adjoining points, as represented in fig. 2, the recesses n being of such a form and size as to receive one of the enlarged portions, o , of the strip shown in fig. 5, the narrow portion l of the strip lying in the passage-way between the adjoining recesses.

Across the passage-way between the recesses n I make a small V-shaped projection or tooth, e , as shown in fig. 1, and, corresponding with these teeth e , on the roll B, I form on the roll C a pair of similar teeth, a , the rolls and their respective teeth e and a being so arranged that, as the rolls revolve, the teeth e will engage between the teeth a , as represented in fig. 1.

It will be seen that, when thus constructed and arranged, if a strip, such as is represented in fig. 1, is fed through between the rolls B, the wider portions o will lie in the recess n , and the narrow parts l will be caught between the teeth e and a , and will be thereby crimped at those points as it is fed through. By this we accomplish two objects; first, the stock is fed to the forming-machine or dies by a positive movement, and all possibility of its slipping is prevented; and, second, the narrow crimped portion of the strip yields readily as the wider portions o are operated upon by the dies, thus allowing the metal to give, or be drawn alike and evenly on all sides of the eyelet as it is formed, and thereby makes it of even thickness entirely around or on all sides of its tubular portion, and also around its entire flange, a very important consideration in the manufacture of eyelets.

To operate these feed-rolls, I place upon the outside of the frame A a vertically-sliding rod or bar, L, which moves in guides, as represented in fig. 3, and to this bar I attach a pawl, r , which engages with the teeth of a ratchet-wheel, P, secured upon the journal of the lower roll B. As the bar L is raised, which is done by connecting it in any suitable manner with the operating mechanism, the pawl engages with one of the teeth of the wheel P, and imparts motion to the rolls, the pawl sliding over the teeth as the bar L is depressed, by which means the strip is fed forward between the rolls at regular intervals.

It will, of course, be understood that this feeding-mechanism will be so located, in relation to the eyelet-forming machine, as to deliver the strip or stock to the dies in a suitable manner to be operated upon thereby, as is usual in this class of machines.

Having thus described my invention,

What I claim is—

The roll B, provided with the recesses n and the teeth e , in combination with the roll C, provided with the teeth a , arranged to operate substantially as described.

THOMAS GARRICK.
